PRODUCTION OF ACID FREE FLOWERS OF
SULPHURAlbert C. Mohr, Berkeley, Calif., assignor to San
Francisco Sulphur Company, a corporation of
California

Application September 30, 1939, Serial No. 297,321

2 Claims. (Cl. 23—227)

This invention relates to the production of substantially acid free flowers of sulphur.

Flowers of sulphur are produced by melting sulphur in a vaporizing pot and discharging the sulphur vapor into a large chamber filled with cold air. The flowers of sulphur which form upon the sides of the chamber, when collected into a mass, have an acid content as sulphuric acid of 0.4% to as much as 2.5%. In addition, only about 50% of the material collected in the chamber is in such a form that it can be classified as flowers of sulphur, the remainder of the sulphur being in undesirable grades of "granulated pile" sulphur and "rock sulphur."

In accordance with this invention, I am able to increase the yield of flowers of sulphur collecting in the chamber to the order of 75% at the expense of the undesirable "granulated pile" and "rock sulphur" produced. In actual operation I have been able to reduce the granulated pile sulphur produced to approximately 24% and the rock sulphur to about 2.5%. At the same time the acid content of the sulphur is reduced to 0.15% and less as sulphuric acid.

I have discovered that by first heating the sulphur to remove or reduce the oxygen content initially present in the atmosphere of the condensing chamber the acid content can be reduced. If the heating is then continued and sulphur vapor thereafter is jetted into the condensing chamber, preferably through a plurality of jets, the beneficial results typifying the present invention will be secured. I appreciate that it has heretofore been proposed to utilize an initially inert atmosphere in the condensing chamber—see British Patent No. 7,086 of 1898. However, while it is quite easy for one to say "employ an inert atmosphere in the condensing chamber," in practice it is something else and, so far as I am aware, the practice of the British patent has never been employed commercially.

I have discovered that if the atmosphere of the chamber is initially deprived of its oxygen by burning of the atmosphere with sulphur in such a manner that the temperature of the flame does not exceed 900° C., and is not what is known in the trade as "high intensity burning", then the acid content of the sulphur will be reduced. This low intensity burning is continued until combustion of the sulphur is no longer supported. The sulphur vapor is then discharged into the now oxygen-lean atmosphere of the chamber, preferably through a plurality of nozzles, and condensed to form the acid free flowers of sulphur. While I have not proven this, a reason-

able explanation appears to be that when high intensity burning is permitted, nitric oxide is formed as well as sulphur dioxide. The conditions are such that in effect one has a "lead chamber process" for the production of sulphuric acid. By operating at a temperature whereat the flame temperature is below about 900° C. nitric oxide formation is prevented and, as a consequence, the so-called acid content of the flowers of sulphur is reduced to 0.15% sulphuric acid and less.

It is in general the broad object of the present invention to provide an improved process for the manufacture of flowers of sulphur.

Another object of the present invention is to provide for manufacture of flowers of sulphur substantially free of acid in a condensing chamber employing ordinary air as the condensing medium.

A further object of the present invention is to provide a suitable apparatus enabling the production of flowers of sulphur, and the yield thereof, to be improved.

The invention includes other objects and features of advantage, some of which, together with the foregoing, will appear hereinafter wherein a practice illustrating the preferred manner and apparatus of the invention is disclosed.

In the drawing, Figure 1 is a diagrammatic view illustrating the apparatus arrangement which can be typically practiced.

Figure 2 is a section through the gooseneck outlet while Figure 3 is a plan view of the orifice plate employed.

In the drawing I have shown a suitable furnace 7 heated by a burner 8 and discharging gases of combustion through flue 9 into a stack 11. A sulphur melting pot 12 is heated by the gases of combustion passing through flue 9. Melted sulphur is discharged through line 13 into gooseneck 14 on a sulphur vaporizing vessel 16 positioned in the furnace 7. Adjacent to the furnace is a cooling chamber indicated generally by numeral 17. As is well known in the art, this is a relatively large brick chamber. Gooseneck 14 discharges into chamber 17 adjacent one end thereof and intermediate the top and bottom and usually centrally of the width.

In operation, liquid sulphur is delivered through pipe 13 into gooseneck 14 and thence into vessel 16. In vessel 16 sulphur is first maintained above its kindling temperature (260° C.) and below that temperature at which any appreciable quantity is discharged into chamber 17. After the oxygen in chamber 17 is exhausted the sulphur is ejected

into chamber 17 by being heated to above its boiling point, 444.6° C.

It is commonly stated that sulphur is sublimed, but this is not strictly correct, because sulphur does not pass from the solid to the vapor state directly. The kindling temperature of sulphur is below its boiling point, about 260° C. As the sulphur is heated in vessel 16, if any oxygen be present sufficient to support combustion, the sulphur burns. Now it is my observation that with the operation of the structure of the Cecon application, direct release of the jet of sulphur vapor into the air filled atmosphere of the condensing chamber caused a high intensity flame adjacent to the nozzle through which the jet was released and, correspondingly, a relatively high acid content.

This high intensity flame is also secured in the operation of such a process as that shown in the French Patents No. 567,658 and No. 574,573 and in the U. S. patent to Walters No. 873,812 of December 17, 1907, and in the U. S. patent to Reed No. 1,518,126 of December 2, 1924. In these, air is blown over the molten sulphur or into contact with hot sulphur vapor. Not only are these processes objectionable in that the heat of the sulphur is transferred to the atmosphere in the condensing chamber and the temperature of the chamber raised but, additionally, the practically unrestricted air-sulphur contact creates a high intensity flame with consequent formation of flowers of sulphur of high acid content.

In accordance with this invention, I permit initial free access of the atmosphere of the condensing chamber 17 with sulphur undergoing heating and vaporizing in vessel 16. This is possible because ordinarily the gooseneck has a relatively large cross-sectional area, the gooseneck which I employ having a diameter of 14 inches. Since the gooseneck has a relatively small volume as compared to the chamber, and since whatever circulation occurs in the gooseneck is due largely to convection, the air quantity available to the sulphur at any instant is relatively small. The sulphur therefore cannot burn rapidly. As a consequence, a low intensity flame is present in the gooseneck. If desired, a suitable sight opening and glass may be provided to observe this flame in the gooseneck. When the oxygen content in the chamber 17 is so low that it will no longer support combustion, as determined either by the usual pyrogallol test, or else by actual observation of the conditions in the gooseneck, I lower nozzle plate 18 into position. The discharge end 21 of the gooseneck 14 is at an angle of about 45° to the vertical and the plate 18 is hinged above it as at 22. A cable 23 extends from ears 24 to a winch indicated generally at 26. The plate carries a plurality of orifices 27 preferably of a relatively small size and I have used a plate on a 14 inch diameter gooseneck having 12 1-inch pieces of stainless steel pipe. The plate carries a seating ring 28 cooperating with a gasket 29 to ensure tight seating so that all sulphur vapor is emitted through the nozzle in the plate. The weight of the plate holds it snugly in place.

With continued and possibly increased heating the sulphur vapor is then discharged upwardly into the oxygen-lean atmosphere of the chamber, in which the oxygen content has been reduced to an extent sufficient that the atmosphere will no longer support combustion with the sulphur. Usually an atmosphere containing less than 10% oxygen is too lean to burn with

sulphur. The plate is left in position until the run is completed.

At the commencement of a new run, after the chamber has been open, the plate is lifted out of position so that free access of the chamber atmosphere to the sulphur undergoing vaporizing in chamber 16 can occur and the oxygen be removed therefrom.

It is to be noted that plate 18, when in position, is at an angle of about 45°. The effect of this, and of the plurality of jets, is to discharge the sulphur vapor upwardly and ensure that adequate and thorough mixing of the sulphur vapor with the inert, cold atmosphere of the chamber 17 occurs. This is particularly advantageous in reducing the amount of rock sulphur produced and increasing, at the expense of the rock sulphur, the yield of flowers of sulphur.

This case is a continuation-in-part of application Serial Number 191,581 filed February 21, 1938.

I claim:

1. In a process for producing substantially acid free flowers of sulphur wherein a mass of sulphur is heated in a vessel and vaporized in said vessel and finally discharged as a vapor at substantially the pressure existing in said vessel into a chamber filled with a cold gaseous atmosphere initially containing oxygen sufficient to support sulphur combustion, the improvement which includes the steps of heating said sulphur mass in said vessel to a temperature of 260° C. and below 445° C. while permitting substantially free access of the chamber atmosphere to said mass in said vessel to consume oxygen in the chamber atmosphere by combustion immediately adjacent to the sulphur mass in said vessel with a flame of relatively low temperature, as compared to the flame temperature when the sulphur is vaporized directly into the chamber and burns therein away from said mass and in contact with the combustion supporting oxygen containing atmosphere of said chamber, and continuing heating of the mass until the oxygen content of said chamber atmosphere is diminished to an extent such that said chamber atmosphere will not support further sulphur combustion while said chamber is substantially free of any sulphur discharge from said mass, and then heating the sulphur to a temperature of at least 445° C. to discharge vaporized sulphur from said mass into said chamber.

2. In a process for producing substantially acid free flowers of sulphur wherein a mass of sulphur is heated in a vessel and vaporized in said vessel and finally discharged as a vapor at substantially the pressure existing on said vessel into a chamber filled with a cold gaseous atmosphere initially containing oxygen sufficient to support sulphur combustion, the improvement which includes the steps of heating said sulphur mass in said vessel to above substantially its kindling temperature and below substantially that temperature at which sulphur vaporizes rapidly from the mass in said vessel and passes over and discharges from said vessel into said chamber while permitting substantially free access of the chamber atmosphere to said mass in said vessel to consume oxygen in the chamber atmosphere by combustion immediately adjacent to the sulphur mass in said vessel with a flame of relatively low temperature, as compared to the flame temperature when the sulphur is vaporized directly into the chamber and burns therein away from said mass and in contact with the combustion sup-

porting oxygen containing atmosphere of said chamber, and continuing heating of the mass until the oxygen content of said chamber atmosphere is diminished to an extent such that

5 said chamber atmosphere will not support further sulphur combustion while said chamber is

substantially free of any sulphur discharge from said mass, and then heating the sulphur to boiling to discharge vaporized sulphur from said mass into said chamber.

ALBERT C. MOHR. 5
